US00D547778S

(12) **United States Design Patent** (10) **Patent No.:** **US D547,778 S**
(45) **Date of Patent:** **** Jul. 31, 2007**

(54) **DRILLING TOOL**

(76) Inventor: **William G. Hodes**, 87 Coachman Way, Sherwood Park, Alberta (CA) T8H 1M3

(**) Term: **14 Years**

(21) Appl. No.: **29/246,747**

(22) Filed: **May 8, 2006**

(51) **LOC (8) Cl.** **15-09**

(52) **U.S. Cl.** **D15/139**

(58) **Field of Classification Search** **D15/138, D15/139, 140; 175/339, 377, 378, 393, 415, 175/417, 418, 420.1, 429, 430; 299/79.1; 407/118**

(57) **CLAIM**

The ornamental design for a drilling tool, as shown and described.

DESCRIPTION

FIG. 1 is a first elevation view of a drilling tool in accordance with the design.

FIG. 2 is a second elevation view of the drilling tool of FIG. 1, viewed from a different angle.

FIG. 3 is a top plan view of the drilling tool; and,

FIG. 4 is a bottom plan view of the drilling tool.

It is to be understood that broken lines in the drawings are intended for illustrative purposes only, and do not form part of the claimed design.
